United States Patent Office

Des. 188,691
Patented Aug. 23, 1960

188,691

PORTABLE ELECTRIC LAMP

Albert Gelardin, 1775 Broadway, New York, N.Y.

Filed July 13, 1959, Ser. No. 56,757

Term of patent 3½ years

(Cl. D48—20)

FIG. 1

FIG. 2

FIG. 3

FIG. 4

Fig. 1 is a side elevational view of a portable electric lamp showing my new design.

Fig. 2 is a rear elevational view thereof.

Fig. 3 is a bottom plan view thereof.

Fig. 4 is a top view thereof.

I claim:

The ornamental design for a portable electric lamp, as shown.
